US00D957488S

(12) **United States Design Patent** (10) Patent No.: **US D957,488 S**
(45) Date of Patent: **** Jul. 12, 2022**

(54) **CONTROL TABLE**

(71) Applicant: **BOBST MEX SA, Mex (CH)**

(72) Inventor: **Antonio Longo, Prilly (CH)**

(**) Term: **15 Years**

(21) Appl. No.: **35/512,566**

(22) Filed: **Mar. 11, 2021**

(80) **Hague Agreement Data**

Int. Filing Date: **Mar. 11, 2021**

Int. Reg. No.: **DM/213235**

Int. Reg. Date: **Mar. 11, 2021**

Int. Reg. Pub. Date: **Sep. 17, 2021**

(51) LOC (13) Cl. **15-10**

(52) U.S. Cl.

USPC **D15/145**
